(74) Attorney, Agent, or Firm—Marshall A. Lerner, Esq.; Finn T. Simmensen, Esq.; Kleinberg & Lerner, LLP

(57) **CLAIM**

The ornamental design for a shoe upper, as shown and described.

DESCRIPTION

FIG. 1 is a perspective view;
 FIG. 2 is a left side elevational view thereof;
 FIG. 3 is a top plan view thereof;
 FIG. 4 is a right side elevational view thereof;
 FIG. 5 is a front side elevational view thereof; and,
 FIG. 6 is a rear elevational view.
 The broken line showing the sole in the figures is for illustrative purposes only and forms no part of the claimed design.
